[57] **CLAIM**

The ornamental design for a sideguard for a birthing bed, as shown and described.

DESCRIPTION

FIG. 1 is a perspective view of a sideguard for a birthing bed, showing our new design;

FIG. 2 is a side elevational view;

FIG. 3 is an elevational view, showing the side opposite that shown in FIG. 2;

FIG. 4 is an end elevational view;

FIG. 5 is an elevational view, showing the end not shown in FIG. 4;

FIG. 6 is a top plan view; and,

FIG. 7 is a bottom plan view thereof.

The broken lines in FIG. 1 are for environmental purposes only and form no part of the claimed design.

FIG. I
